United States Patent

Des. 238,804

Patented Feb. 10, 1976

238,804

DOG TOY

John Holden, Line Ridge Farm, R.D. #1,
Mount Joy, Pa. 17552

Filed July 23, 1974, Ser. No. 491,044

Term of patent 14 years

Int. Cl. D21—01

U.S. Cl. D34—15 B

FIG. 1

FIG. 4

FIG. 2

FIG. 3

FIG. 5

FIG. 1 is a side elevational view of a dog toy showing my new design;

FIG. 2 is a top plan view thereof;

FIG. 3 is a bottom plan view thereof;

FIG. 4 is a front elevational view thereof; and

FIG. 5 is a rear elevational view thereof.

I claim:

The ornamental design for a dog toy, substantially as shown.
